UNITED STATES PATENT OFFICE.

GRACE HUNTINGTON BUCKLAND, OF FREMONT, OHIO.

DESIGN FOR FABRIC.

SPECIFICATION forming part of Design No. 36,241, dated March 3, 1903.

Application filed July 18, 1901. Serial No. 68,856. Term of patent 3½ years.

To all whom it may concern:

Be it known that I, GRACE HUNTINGTON BUCKLAND, a citizen of the United States, and a resident of the city of Fremont, in the 5 county of Sandusky and State of Ohio, have invented and produced a new, original, and ornamental Design for Fabrics, of which the following is a specification, reference being had to the accompanying drawing, forming 10 a part thereof.

This design relates to the ornamentation of cotton, silk, woolen, paper, celluloid, and other fabrics.

The drawing embodying my design consists 15 of a wreath of clematis, original in design, whose stem, flowers, and leaves are conventionally and artistically arranged surrounding a shield centrally located. Within this wreath and below the shield is a scroll of 20 original design. The flowers of this wreath are disposed at more frequent intervals than found in nature on the vine relative to the number of leaves. The flowers are emphasized in position. Those with full face are 25 located one at the upper, one at the lower, and one at each middle portion of the wreath.

A flower in side view and as if blushingly hiding its face, but contributing by suggestion to the general effect, is found between each full-faced flower. These intermediate 30 flowers are disposed relatively to the stem, so that the major portion of each of them is inside of the stem, and thus contribute to the symmetry of the wreath and also artistically contribute to lessen and improve the 35 otherwise blank spaces between the stem and the shield. Leaves and buds are also disposed so as to add symmetry to the wreath and also suggest luxuriance of growth and foliage relative to the wreath. 40

Having described my invention, what I claim as new, and desire to secure by Letters Patent, is—

The ornamental design for a fabric herein shown and described. 45

In testimony whereof I have signed my name to this specification in the presence of two subscribing witnesses.

GRACE HUNTINGTON BUCKLAND.
